CLAIM

The ornamental design for a glove holder, as shown and described.

DESCRIPTION

FIG. 1 is a front elevation view of a glove holder showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is an in-use perspective view thereof.

The broken lines in FIG. 7 of the drawings depict a portion of a golf cart and golf gloves as environmental subject matter only and form no part of the claimed design.
